UNITED STATES PATENT OFFICE

2,105,987

KNITTED FABRIC

Joseph P. Primm, Rome, Ga.

Application June 29, 1936, Serial No. 88,926

1 Claim. (Cl. 66—172)

This invention relates to improvements in knitted fabrics, and its objects are as follow:

First, to provide an accordion knitted fabric or stocking top in which an elastic thread is so fed as to lie on one face of the fabric, to and against which it is secured by a tying yarn or thread, which, in addition to anchoring the elastic thread, is also knitted into the fabric so as to hold adjacent wales together.

Second, to apply an elastic thread to a ribbed fabric in the foregoing manner, the tying-in thread serving to hold adjacent wales of said fabric in close relationship.

Third, to utilize a mock ribbed fabric on which an elastic thread is tied in the manner above described, as a so-called garter top for hosiery.

Other objects and advantages will appear in the following specification, reference being had to the accompanying drawing in which:

Figure 1 is an elevation of a portion of an article of hosiery, the external wales of the garter top being fragmentarily shown.

Figure 2 is a fractional diagram of the courses and wales of the fabric, the view being an interior elevation.

In the drawing, 1 designates a portion of an article of hosiery, which in this instance is a sock, although it may be regarded as of some other species. Further, the invention is not necessarily embodied in an article of hosiery because it would be as effective in flat knitted goods.

The sock 1 has a garter top 2, so called because it has an elastic thread 3 (Fig. 2) which produces a contracting effect upon the leg of the wearer. This elastic thread is either covered or not, and it is fed in a single, unbroken strand from a spool supported by the circular knitting machine later referred to.

The fabric 4 in Fig. 2 is the same as the top 2 in Fig. 1. Being so, the mock ribs 5 in Fig. 1 are identified between the wale lines 6 and 17 in Fig. 2. These ribs are separated by the intervening wales 17, shown in Fig. 2 but concealed in Fig. 1 because of the natural contraction of the fabric, due, partly, to this inherent quality of ribbed fabric and partly to the elasticity of the thread 3.

There is very little initial tension in the elastic thread 3. It is inlaid in the process of knitting, and is not itself knitted in. The term "inlaid" only explains how the elastic thread is fed to the fabric as the latter is knitted. The elastic thread is not incorporated in the fabric 4 itself. That is to say, it is not carried over and under the loops of wales 6, 17, nor is it interspersed between said wales. The final result of inlaying the elastic

thread 3 is to apply it or make it lie against one face of the fabric 4, and this is accomplished by a tying-in thread 7, supplied at a feed point of the machine other than those at which the body thread or threads of the fabric 4 and the elastic 5 thread 3 are introduced.

Said tying-in thread 7 occurs in a continuous strand but because of the fact that it is knitted into the fabric by a set of needles different from the set which is used to pull the elastic thread 10 down to the inlaying level, in other words down to the sinker throats, said tying-in thread produces one or more extra courses 8, located between the elastic thread courses. However, the tying-in thread follows the elastic thread courses, 15 as shown, periodically crossing the elastic thread at 9, first in one direction, next in the other direction.

The direction-change points are designated 10, and it is at these points which occur medially of 20 the wale lines 6 that the tying-in thread 7 is formed into stitches 11 which are interlooped both with the short loops 12 in one body-thread course and with the loop tops 13 of the corresponding short loops 12 in the next body-thread 25 course. Thus the elastic thread is held against the face of the fabric 4 by the tying-in thread 7 which simultaneously secures the elastic thread and interloops with the loops 13 of adjacent wales 6. This last interloopment prevents the fabric 30 from unraveling.

It will be noted that the tying-in thread 7 (also 8) disappears into the fabric 4 only along the wale lines 17. At the places where it emerges from the fabric it floats across at least one intervening wale line 6. It is at its float places that the tying-in thread 7 crosses the elastic thread 3 to secure the latter to the face of the fabric 4.

It is of importance to note the advantages of supplementing the fabric with an elastic thread. 40 In the event of breakage of the elastic thread, said fabric still holds its shape and retains its natural holding function. When an elastic thread is embodied in a plain fabric not of the mock rib or accordion type the rib effect depends entirely on 45 the puckering of the elastic. Should the elastic break in such fabric the ribs will simply flatten out and become a plain flat fabric. If such fabric happens to be a stocking top there will be no appearance of a rib top.

In fixing the machine to produce the improved fabric, the elastic thread is pulled down by every fourth needle, but some other multiple may be used, this as desired. The elastic thread is thus pulled down to the sinker throats, as previously 55

stated. The three needles between the foregoing working needles are held depressed below the sinkers so as not to interfere with said working needles from taking the elastic thread.

5 After taking the elastic thread as stated, the hooks of the working needles hold the elastic thread down in the sinker throat until it reaches the feed point of the tying-in thread. It is at this feed point that the elastic thread slides off of the 10 working needles, being interlaced by the tying-in thread as explained.

If desired, the working needles may be used in pairs, triples or other combinations, instead of in singles as here. Then, instead of anchoring 15 the elastic thread with a single yarn, it would be

held down with two or more threads. The instant sock is made on a circular knitting machine with a multiple body yarn feed.

I claim:

An accordion stocking top comprising two 5 threads, one of said threads being knitted into alternate courses in every wale, the other one of said threads being knitted in intermediate courses in alternate wales and floated across intervening wales, and an unknitted elastic thread incorporated in said stocking top in spaced courses and secured to said stocking top by the floats of said 10 second mentioned thread.
